CLAIM

The ornamental design for a display screen or portion thereof with graphical user interface, as shown and described.

DESCRIPTION

FIG. 1 is a front view of a display screen with graphical user interface, showing a first embodiment of the new design; FIG. 2 is a front view, showing a second embodiment thereof;

FIG. 3 is a front view, showing a third embodiment thereof; and,

FIG. 4 is a front view, showing a fourth embodiment thereof. The broken line showing of the display screen or portion thereof are included for the purpose of illustrating environmental structure and form no part of the claimed design. The broken line showing of text and portions of the graphical user interface are included for the purpose of illustrating portions of the article and form no part of the claimed design.

1 Claim, 4 Drawing Sheets
